CLAIM

(62) Division of application No. 29/487,518, filed on Apr.
9, 2014, now Pat. No. Des. 734,012.

The ornamental design for an insole, as shown and
described.

(51) **LOC (10) Cl.** **02-04**

DESCRIPTION

(52) **U.S. Cl.**

USPC **D2/961**

(58) **Field of Classification Search**

USPC D2/896, 908, 925, 946, 947, 949, 950,
D2/954, 961, 968; 36/2.6, 115, 116, 137,
36/139-141; 219/211; 301/5.301, 5.303
CPC A43B 7/04; A43B 7/16; A43B 7/22;
A43B 13/38; A43B 13/40; A61F 5/14;
A63C 17/08

See application file for complete search history.

FIG. 1 is a top front perspective view of a left side insole,
showing our new design;

FIG. 2 is a top plan view thereof;

FIG. 3 is a bottom plan view thereof;

FIG. 4 is a side view thereof;

FIG. 5 is an opposite side view thereof;

FIG. 6 is a front view thereof; and,

FIG. 7 is a back view thereof.

A right foot insole is a mirror image of FIGS. 1-7.

The broken lines on the side walls in FIGS. 1-5 and 7 are

included to show an unclaimed abutment between a first

layer and a second layer of the insole only and form no part

of the claimed design. All broken lines in FIGS. 1-7 are

included to show unclaimed subject matter and form no part

of the claimed design.
